US00D978941S

(12) **United States Design Patent** (10) **Patent No.:** **US D978,941 S**
(45) **Date of Patent:** **** Feb. 21, 2023**

(54) **ROBOTIC ARM**

(71) Applicant: **Auris Health, Inc.**, Redwood City, CA (US)

(72) Inventor: **Frankie Vazquez**, San Francisco, CA (US)

(73) Assignee: **Auris Health, Inc.**, Redwood City, CA (US)

(**) Term: **15 Years**

(21) Appl. No.: **29/721,949**

(22) Filed: **Jan. 24, 2020**

Related U.S. Application Data

(62) Division of application No. 29/634,027, filed on Jan. 17, 2018, now Pat. No. Des. 873,878.

(57) **CLAIM**

The ornamental design for a robotic arm, as shown and described.

DESCRIPTION

FIG. 1 is a top, front, right perspective view of a robotic arm; FIG. 2 is an enlarged view of a portion of FIG. 1; FIG. 3 is an enlarged view of another portion of FIG. 1; FIG. 4 is a right-side view of the robotic arm; FIG. 5 is an enlarged view of a portion of FIG. 4; FIG. 6 is a left-side view of the robotic arm; FIG. 7 is an enlarged view of a portion of FIG. 6; FIG. 8 is a rear view of the robotic arm; FIG. 9 is an enlarged view of a portion of FIG. 8; FIG. 10 is a front view of the robotic arm; FIG. 11 is an enlarged view of a portion of FIG. 10; FIG. 12 is an enlarged view of another portion of FIG. 10; FIG. 13 is a top plan view of the robotic arm; and, FIG. 14 is an enlarged view of a portion of FIG. 13. The broken lines illustrate portions of the robotic arm and form no part of the claimed design.

1 Claim, 8 Drawing Sheets
